[57] **CLAIM**

The ornamental design for a bread server, as shown and described.

DESCRIPTION

FIG. 1 is a top, front, and side perspective view of a bread server showing my new design, with the cutting board portion removed for ease of illustration;

FIG. 2 is an exploded perspective view thereof;

FIG. 3 is a top plan view thereof;

FIG. 4 is a bottom plan view thereof;

FIG. 5 is a front elevation view thereof;

FIG. 6 is a rear elevation view thereof;

FIG. 7 is a left side elevation view thereof;

FIG. 8 is a right side elevation view thereof;

FIG. 9 is a cross-section thereof taken on line 9—9 in FIG. 3;

FIG. 10 is a cross-section thereof taken on line 10—10 in FIG. 3;

FIG. 11 is a top, front, and side perspective view of a bread server with the cutting board between the base and lid/tray portions;

FIG. 12 is an exploded perspective view of FIG. 11;

FIG. 13 is a cross-section taken on line 13—13 in FIG. 11;

FIG. 14 is a top, front, and side perspective view of a bread server in an alternate position with the lid/tray inverted and the cutting board overlying the lid/tray;

FIG. 15 is an exploded perspective view of FIG. 14; and,

FIG. 16 is a cross-section taken on line 16—16 in FIG. 14.
